UNITED STATES PATENT OFFICE.

EUGENE A. TOWLE, OF ST. PAUL, MINNESOTA.

DESIGN FOR A CAN OR SIMILAR ARTICLE.

50,453.

Specification for Design.

Patented Mar. 13, 1917.

Application filed August 9, 1915. Serial No. 44,655. Term of patent 14 years.

To all whom it may concern:

Be it known that I, EUGENE A. TOWLE, a citizen of the United States, residing at St. Paul, in the county of Ramsey and State of Minnesota, have invented a new, original, and ornamental Design for a Can or Similar Article, of which the following is a specification, reference being had to the accompanying drawings, forming part thereof.

In the drawings

Figure 1 is a front elevation of my improved vessel; and

Fig. 2 is an end elevation of the same.

I claim:

The ornamental design for a can or similar article, as shown.

EUGENE A. TOWLE.
